UNITED STATES PATENT OFFICE.

JOHN E. HANIFEN, OF PHILADELPHIA, PENNSYLVANIA.

DESIGN FOR STOCKING FABRIC.

SPECIFICATION forming part of Design No. 11,682, dated March 16, 1880.

Application filed November 29, 1879. Term of patent 3½ years.

To all whom it may concern:

Be it known that I, JOHN E. HANIFEN, of the city and county of Philadelphia, and State of Pennsylvania, have originated and designed an Ornamental Stocking Fabric, of which the following is a full, clear, and exact description, reference being had to the accompanying photographic illustration, making part of this specification.

10 *a* represents the plain ground of a piece of full-length or half hose. *b* represents a series of parallel tuck-stitches, which extend the length of the hose or stocking; and *c* represents a series of parallel tuck-stitches, which

15 extend parallel in either direction of the fabric. Each row of stitches *b* forms a continuous line, and the stitches *c* form broken lines,

the series whereof alternate with the continuous lines of stitches *b*, the whole forming neat, tasty, and attractive design.

The fabric is produced by the usual plai stitch and tuck cams.

What I claim as my invention is—

The ornamental design for stocking fabric, consisting of the plain ground *a*, having continuous lines of single tuck-stitches *b* and broken lines of tuck-stitches *c* alternating therewith, substantially in the manner above described and illustrated.

JOHN E. HANIFEN.
